PRINTING DEVICE

George W. Schaefer, Quincy, Mass., assignor, by
mesne assignments, to Addressograph-Multi-
graph Corporation, Cleveland, Ohio, a corpora-
tion of Delaware

Application July 27, 1935, Serial No. 33,522

26 Claims. (Cl. 101—56)

This invention is concerned with a system of printing sales slips and the like, involving the use of a customer's token evidencing his credit standing. Such systems are now frequently employed in large retail stores, where a metallic token, in the form of an embossed address plate, is issued to a customer entitled to a certain amount of credit. The same token may apply to several different stores, each store having an individual indication on the token not applicable to any of the other stores. When the customer presents his token to the proper store, the salesman utilizes it in printing one or more sales slips, and if desired an entry in the salesman's sales book, with the result that credit is given only to those entitled to it, the address on the account slip and the delivery slip is necessarily correct, and there is a material saving in time in making out such slips.

It is an object of the present invention to provide a printing device, utilizable in the above outlined system, which shall effectively and visibly reject tokens not intended for that machine, so that no explanation will be necessary by the salesman to show the customer that he is not entitled to credit on the basis of that token.

Another object of the invention is to so devise the printing mechanism that the raising of the platen arm will cock a roller platen mechanism, whereupon when the platen is in position, the manual release enables rapid printing by rolling action with a definite printing pressure, independent of the manual force applied by the operator.

Another object of my invention is to enable the printing device to carry changeable printing matter additional to the token, which, however, when installed, may be imprinted with each token. This provides for the printing on the sales slip of such matters as the date, department numbers, etc.

I have devised my printing device so that it may readily receive a token in the form of an embossed plate having in its edge a notch, the position of which identifies the token with the particular store. To prevent the user of the token from soiling his hands, due to the action of the inking ribbon overlying the token in printing, I provide a cover for the printing plate which is hinged to one end thereof and into which the plate may be snapped when not in use. This cover acts also as a handle for the ready insertion of the plate in the machine, or its withdrawal therefrom.

My invention is hereinafter more fully described in connection with a preferred embodiment thereof illustrated in the drawings, and the essential novel features are summarized in the claims.

In the drawings, Fig. 1 is a side elevation of the

token printing machine in its cocked condition ready for printing from an inserted token; Fig. 2 is a similar view showing the condition of the parts after the printing has been effected; Fig. 3 is a plan of the token printer; Fig. 4 is a longitudinal vertical section of the printer indicated by the line 4—4 on Fig. 3; Fig. 5 is a transverse vertical section through the printer indicated by the line 5—5 on Fig. 1; Fig. 6 is a side elevation of the printer with platen raised into the position which cocks the platen carriage; Fig. 7 is a sectional plan of the printer just above the bed, as indicated by the line 7—7 on Fig. 6; Figs. 8 and 9 are diagrammatic plans showing the action on the control mechanism of a token intended for that machine and one not so intended, respectively; Fig. 10 is a vertical longitudinal section showing the action of the platen arm in releasing an improper token. The remaining figures show the token itself, Fig. 11 being a face view of the closed device looking at the cover; Fig. 12, a cross section on the line 12—12 on Fig. 11, and Fig. 13 a view looking at the token open and ready for insertion in the machine.

Referring first to Figs. 11, 12 and 13, the token shown comprises an embossed printing plate 1 and a flanged cover 2 hinged to the plate at adjacent ends. The plate has depressed marginal portions 3, 4, a projecting tongue 5 at the free end, while the other end is curled over into an ear 6. The cover plate is formed with a flange 7 extending entirely around it. Adjacent the printing platen a slit 8 is formed in the cover plate and flange to provide a bar portion about which the ear 6 extends. At the other end of the cover plate the flange is cut down at 9 to receive the tongue 5.

When the token is folded in position for storage, the printing plate seats within the flange 7 of the cover, as illustrated particularly in Fig. 12. The free end of the printing plate makes a snug enough engagement with the flange 7 on opposite sides of the notch 9 so that the plate remains normally within the cover. The projecting tongue 5, however, allows the token to be readily opened, the operator grasping the cover side edges, for instance, between the thumb and one or more fingers of the left hand and placing a finger and thumb of the right-hand against the hinge ear and the tongue 5. A slight longitudinal pressure on the tongue then allows the ready opening of the token so that it comes into the position illustrated in Fig. 13.

In order to identify tokens with a particular store, I form on one of the edges of the printing plate 1 a notch 10. The position of this notch in

such edge determines the store to which the token corresponds, as all the printing machines of that store have a controlling member hereinafter described, adapted to enter such notch. Any token with the notch in any other position will, accordingly, not allow the controlling member to take the position it would if the notch were in a proper position for that store, and this abnormal position of the controlling member operates mechanisms hereinafter described to discard such improper token.

The plate portion 1 of the token is embossed with suitable printing characters 12, which are struck up from the bottom of the plate portion 15 and thus when the token is closed are housed within it and protected from injury. Within the cover 1 place an identification card 13, which may carry an imprint of the embossed matter and is of such contour that it fits snugly within the 20 flange of the cover.

The printing machine in the embodiment shown is designed to print from the printing plate of the token just described, while the cover portion of that token acts as a handle for the insertion but extends idly at the front of the machine during the printing operation. I will now describe such printing mechanism.

In Figs. 1 to 10 inclusive, 20 designates the bed of the machine which is shown as a hollow rectangular member having a horizontal top plate 21 and a vertically depending skirt at the ends and sides. Rising from the top are a pair of ears 25 carrying a shaft 26 which is embraced by a tubular portion 31, formed on the platen arm 30, 35 thus enabling this arm to be substantially horizontal as shown in Figs. 1 and 2, or vertical as shown in Fig. 6.

On the forward end of the platen arm is formed a head 32 which constitutes a rigid part 40 of the arm. This head has grooves 33 at its opposite sides. Slidably embracing the arm 30 is a carriage 40, U-shaped in horizontal cross-section. The transverse portion of this carriage surrounds the arm and is guided thereby while 45 the side portions carry on the inner faces rollers 42 occupying the respective grooves 33 of the head. At its lower forward portion the side members of the carriage carry a support for the transverse shaft 45 on which is a roller platen 46.

An adjustable stud 35 carried by the platen arm is adapted to engage the bed platen 21 and limit the lowermost position of the arm. The platen head 32 is provided within the grooves 33 with shims 37 adjustable by screws 38. By these 55 means the position and path of the roller platen is accurately effected, so that it may move horizontally with the desired printing pressure against the token on the bed, as hereinafter described.

The carriage 40 is connected by a link 50 to an arm 51 which is loosely journaled on the shaft 26. Pivoted to the arm 51 is a catch 52 pressed in a downward direction by a spring 54 and designed to coact with a leaf spring retainer 55 secured to the rear end of the bed 20. This construction serves to retain the elevated platen arm in vertical position against inadvertent displacement, as illustrated in Fig. 6, while allowing it to be readily lowered manually when desired. It will be seen from Fig. 6 that in this raised position other leaves of the spring 55 engage the arm 51 and limit its movement, with the result that the link 50 holds the carriage 40 in its foremost position. A pair of coiled tension springs 75 57 are connected at their forward ends to ears

58 on the carriage and at the rear ends to a rod 59 secured to the platen arm.

It results from the construction described that when the platen arm is in a substantially horizontal position the tension of the springs 57 tends to draw the carriage to the rearmost position, as shown in Fig. 2. As the arm is raised, the effect of the link 50, swinging about the pivot at the upper end of the restrained arm 51 is to shove the carriage lengthwise of the arm 30 toward the free end thereof. When the arm comes into the vertical position shown in Fig. 6, the carriage is at the extreme end of the platen arm. In this position a flange 48 at the rear end of the carriage becomes engaged by a shoulder on a latch 60, pivoted to an ear 61 rising from the arm and pressed toward the arm by a spring 62.

It will be seen that the raising of the platen arm to a substantially vertical position not only forces the carriage forwardly but cocks it; that is to say, restrains it in that position under the action of the extended springs 57, and the carriage remains in that position when the arm is lowered for use into position as shown in Fig. 1.

A trigger for releasing the cocked carriage comprises a rocking bar 65 pivoted to a stud 66 rising from the head 32 of the platen arm. This platen has in its rear a notch which receives a forward extension 63 of the latch 60. The other end of the rocking bar carries a knob 67 for manual use. Beneath the knob the rocking bar rests in a vertical plunger 68, slidably mounted in the head 32 and pressed upwardly by a spring 69 (Fig. 5).

It will be understood from the description given 35 that when the platen arm is raised into the vertical position, the carriage is forced forwardly and is latched by the latch 60, and that when the arm is thereafter lowered, as it may be by giving its upper end a slight jerk, causing the catch 52 40 to come free from the spring 55, the parts assume the position shown in Fig. 1 with the carriage cocked. Thereafter a manual blow or downward pressure on the knob 67 rocks the bar 65 to force upwardly the latch 60, releasing the carriage, and thereupon the springs 57 pull the carriage rearwardly so that the platen 46 rolls over the surface beneath it. As about to be explained, such surface may include the embossed portion of the token whereby printing may be effected on 50 a sales slip or other paper overlying the token.

Coming now to the means for carrying the token in the machine, it will be seen from Fig. 5 that the horizontal bed plate 21 of the machine is recessed with a shallow undercut groove to 55 form a slideway for a slide 70. This slide is formed in its top surface with a shallow groove adapted to receive the printing member 1 of the token. The top of this shallow groove is formed by horizontal plate-like ribs 72 and 73 on the 60 slide, which overhang the depressed margins 4 and 3, respectively, of the token. The token may therefore be readily shoved into place lengthwise of the slide, the hinged cover 2 of the token extending idly beyond it and being 65 supported in substantially horizontal position by the slide as illustrated in Figs. 6 and 7.

The slide 70 preferably has another shallow groove 75 parallel with the groove 71 and bounded by the overhanging portion of the rib 73 and 70 another rib 76. This slideway may accordingly receive any characters intended for continuous printing on successive slips, as, for instance, a small embossed plate carrying numbers to indicate the date and other small embossed plates to 75

5 indicate the department. If such characters were employed the department indication would remain permanently in the machine so long as it was associated with that department, whereas the date would be changed every day. The additional printing matter is printed at the same time with the token by the same platen 46. I have shown the platen as having an intermediate annular groove 47 between two larger portions which coat with the token and the additional matter respectively.

10 The slide 70 may project beyond the bed 21, as illustrated in Fig. 7, but in its innermost position it is entirely over that bed, as illustrated in Figs. 8 and 9. A suitable spring 80 within the hollow base (see Figs. 4 and 10) is anchored at one end to a pin 81, carried by the top plate 21 of the bed and at its other end by a pin 82 depending from the slide 70, and accordingly this spring tends to pull the slide into its outermost position, indicated in Fig. 7.

15 The slide 10 is normally restrained in its innermost position by the engagement of a tooth 85 in a notch 86 in the slide. This tooth is shown as extending upwardly from a rocking bar 87, pivoted to a rod 88, extending crosswise of the base, the other end of the bar being pressed downwardly by a leaf spring 89. The tooth 85 is inclined upwardly from the front of the machine so that when the slide is manually shoved inwardly it cams the tooth downwardly and the returning tooth entering the notch 86 holds the slide normally in its rearmost position, and that is the position for printing from the

20 token.

Pivoted to the underside of the bed plate 21 on a vertical pivot 91 is a flat horizontal bar 90, the rear end of which is turned upwardly at 92 through an opening 93 in the bed plate. A spring 95 attached to the underside of the bed and to the arm 90 tends to swing it in a direction to cause that portion of the arm in front of the pivot 91 to move toward the token 1. Such portion of the arm carries an upwardly extending pin 97 which is in registration with the notch 10 of a properly positioned token appertaining to that machine. Accordingly, if the proper token is inserted, the notch 10 allows the spring 95 to swing the arm 90 into the position shown in Fig. 8, whereas if the token is unnotched, or if the notch is located in some other region the edge of the rib 3 will form an abutment to the pin 97, and the spring will be unable to move the arm and it will remain in the position shown in Fig. 9. Now the position of the upper projection 92 of the arm 90 determines whether or not the printing may be effected from that token, as about to be described.

25 Secured to the tubular hub 31 of the platen arm 30 is a comparatively stiff leaf spring 99. That spring is so positioned that when the controlling pin 97 engages the notch 10 of the token as shown in Fig. 8, the spring is out of registration with the end 92 of the arm 90 when the platen arm is lowered and moves idly past such end, as illustrated in Fig. 1, and hence there is no operation of the controlling mechanism by such spring 99.

30 Now, if, due to the absence of a properly positioned notch, the token plate 1 has swung the bar 90 aside, as shown in Fig. 9, the bar will overhang the latch bar 87 in front of the pivot thereof and the end 92 of the bar 90 will be beneath the spring 99. Then when the arm 30 is lowered, the spring 99 will engage the abutment

35 92 and thus push the rear portion of the arm 90 downwardly into the position shown in Fig. 10, which rocks the bar 87 to withdraw the tooth 85 from the slide 70. Thereupon the spring 80 moves the slide into the outermost position as 40 illustrated in Fig. 7. This ejects the token and shows at once that such token is not suitable for that machine.

45 Any suitable means may be employed for supplying the pigment to make the imprint. For example, I may use sales slips interleaved with carbon strips to effect the printing in that manner. I prefer, however, to mount an inking ribbon in the base of the machine, such ribbon extending intermediately across the region of the token and across the other matter to be printed.

50 I have shown in Fig. 5 a pair of slotted spools 100 and 101 mounted in the base, terminating at the outer ends in knurled heads 102 by which either spool may be turned. An inking ribbon 103, wound on one spool, may pass upwardly through a slot 105 in the bed plate 21, thence across the slide 70 downwardly through the corresponding slot 106 to the other spool 101. Such inking ribbon may conveniently be faced on its 55 underside with a non-inking protection to keep from soiling the token. When any particular region of the ribbon becomes worn the rotation of the corresponding knob 102 a short distance would bring a fresh portion of the ribbon into 60 position for use.

65 The bed may carry suitable guides for the sales slips. For instance, there may be a side guide 111 secured to one side of the bed, as shown in Fig. 5, and thin metal shields 112 may overhang the rear portion of the slide, and other thin sheet metal shields employed, as desired, to restrict the action of the platen to merely the embossed matter on the token and on the additional printing members, so that there would be 70 no tendency to smudge the marginal portions of the sales slip. These are details which may be employed as desired.

75 In changing the dates or other additional matter on the slide, it is a convenience to have the slide project from under the ribbon, and from under any shield which may be employed beneath the ribbon conveniently and to enable this to be accomplished without regard to the action of the platen arm, I secure a flat spring leaf 120 to 80 the underside of the bed plate 21, this leaf having an arm 121 extending over the arm 87, which carries the slide latch 85, and having an upward projection 122 by which it may be manually depressed whenever desired. Such depression causes the arm 121 to depress the latch lever, withdrawing the latch tooth 85 from the slide and allowing the slide spring 80 to project the slide so that the portion thereof normally beneath the ribbon is exposed in front.

85 It will be understood from the description given that I have provided a very simple form of token which may be readily folded and carried by the user in his pocket or purse and readily unfolded for use whenever presented in 90 connection with a purchase. Such token is very easily inserted in the machine which may stand with the arm raised and the printing carriage cocked; then immediately upon insertion the operator simply places the sales slip over the 95 inking ribbon, brings down the arm, pressing or striking down upon the knob. The released carriage thereupon rolls the platen quickly across the printing members to effect the printing.

95 The printing action by the springs 51, when

- released by the operator pressing down on the knob 65, takes place before the operator can remove his manual pressure on the knob, which has been holding the arm stud 35 against the bed. Accordingly, the guide for the platen carriage is held in a definite horizontal position over the bed during the stroke of the platen, resulting in an accurate, well-formed imprint.
- As soon as the token is printed, the salesman withdraws the token from the machine, using the extended cover as a handle to draw it out, closes the token and returns it to the owner with the sales slip, and throws back the platen arm to vertical position to cock the carriage ready for the next imprint. The operation of the cocking and printing continues successively so long as the proper tokens are presented.
- As soon as an improper token is presented the mere lowering of the platen before there is any printing action causes the slide to move outwardly carrying the token beyond the inking ribbon and platen, and showing at once that printing from that token is impossible. Thereupon the salesman removes the token and no sale is made. The salesman may return the token to the customer with the statement that the machine shows it is not available at that store.
- I claim:
1. In a printing device the combination, with a platen and means to support a token with which the platen may cooperate to print, of means to shift said supporting means in a manner to prevent printing from a token not correlated with the machine.
  2. In a printing device, the combination of a bed adapted to support a token having printing characters, a platen adapted to coact with such characters to effect printing, and control mechanism on the machine adapted to be set by a token to automatically move said token in its own principal plane and thereby discharge such token, said mechanism being non-effective if an indication on the token properly corresponds with said control mechanism.
  3. The combination with a plurality of customer's tokens, one of which has a selective indication in one position and another of which has no such indication in that position, a printing machine adapted to print from a token of the first-mentioned character, a holder to carry a token, and a discarding device on the machine operating automatically to shift said holder to a predetermined position and thereby eject a token of the last-mentioned character before printing can be effected.
  4. The combination with a plurality of customer's tokens, one of which has a notch in its edge in one position and the other of which has no notch in such position, a printing machine adapted to print from tokens, a holder carried by said machine for a token and a discarding device on the machine under the control of a member adapted to enter the notch of a proper token, said discarding device operating automatically to shift said holder to a predetermined position and thereby eject an improper token before printing can be effected.
  5. In a printing device of the character described, the combination, with a platen and means to support a token with which the platen may cooperate to print, of means operating automatically consequent upon a movement of the platen to eject a token not correlated with the machine before printing can be effected.

6. In a printing machine, the combination of a bed to support a token, a platen arm, a platen thereon, mechanism whereby the lowering of the platen arm effects the discharge of an improper token before the platen can effect printing.

7. In a token printing machine, the combination of a bed, a platen arm pivoted thereto, a roller platen carried by the arm, means on the bed for holding a token in position to be engaged by the roller platen as it moves along the lowered platen arm, and mechanism coacting with the token and operative consequent upon the lowering of the platen arm to effect the discharge of an improper token before the platen comes into position to print from the token.

8. In a printing machine, the combination of a bed adapted to carry a form, a raisable platen arm carried thereby, a roller platen on the arm, means for constraining the platen and latching it under constraint when the arm is raised, and mechanism adapted to release the latch at a time when the arm is lowered, whereby the platen may automatically travel across the form.

9. In a printing machine, the combination of a bed adapted to carry a printing form, a raisable platen arm carried by the bed, a roller platen on the arm, spring means adapted to move the platen along the arm, means for latching the platen with the spring means, and a manually operable device carried by the platen arm and serving under pressure of the operator's hand to hold the platen arm in its depressed position and to release the latch, whereby the spring means may cause the platen to roll over the form.

10. In a printing machine, the combination of a bed adapted to carry a printing form, a platen arm carried by the bed and adapted to raise therefrom, a roller platen slidably mounted on the arm, spring means tending to move the platen bodily along the arm, mechanism operating automatically consequent upon the raising of the arm to move the platen bodily in opposition to the spring means, means for latching the platen in its constrained position when the arm is raised and retaining the platen in this position while the arm is being lowered, and a manually operable device carried by the platen arm and serving under pressure of the operator's hand to hold the platen arm in its depressed position and to release the latch.

11. In a printing machine, the combination of a bed, a movable platen arm, a bodily movable roller platen on the arm, a shiftable slide on the bed, means on the slide for carrying a customer's token in position to be engaged by the roller platen when the platen arm is lowered, and means for rolling the platen across the token.

12. In a printing machine, the combination of a bed, a movable platen arm, a shiftable slide on the bed adapted for carrying a customer's token in position to be engaged by the platen, means acting consequent upon the lowering of the platen arm to release the slide if the token is not properly correlated with the machine, and spring means operating to move the released slide.

13. In a printing machine, the combination of a bed, a slide mounted thereon having means for movably carrying a customer's token, a spring tending to move the slide in a direction away from the bed, a latch to hold the slide in an active position, a pivoted platen arm carried by the bed, a platen carried by the arm, and mechanism under the control of the customer's token on the slide to effect the release of the slide latch consequent upon the lowering of the platen arm.

14. In a printing machine, the combination of a bed, a movable platen arm, a bodily movable roller platen on the arm, a shiftable slide on the bed, means on the slide for carrying a customer's token in position to be engaged by the roller platen while the platen arm is lowered, and mechanism on the machine controlled by the token to automatically release the slide, said mechanism being non-effective if the indication on the token properly corresponds with said mechanism.
15. In a printing machine, the combination of a plurality of seats, means for holding printing matter in one of the seats indefinitely for successive impressions, means for holding a customer's token on the other seat for one impression, a platen adapted to coact simultaneously with printing matter on both seats, and means for preventing such coaction if the customer's token does not correspond to that machine.
16. The combination of a bed, a slide mounted thereon having a plurality of seats, one for relatively permanent matter and the other for a customer's token changeable for each impression, a platen adapted to coact with both the token and the relatively permanent form, control mechanism for the slide adapted to coact with the token to move the slide automatically when the token does not correspond with the control mechanism such movement being adapted to carry the customer's token beyond the region of the platen.
17. In a printing machine, the combination of a bed, a platen arm carried thereby, a slideable carriage on the arm, a roller platen on the carriage, a spring acting on the carriage tending to move it in one direction, mechanism connected with the carriage operating to move it in the other direction consequent upon the elevation of the arm, automatic means for latching the carriage in the position in which the elevation of the arm has brought it and retaining such position during the lowering of the arm, and mechanism to release the latch to enable the spring to carry the roller across the printing form on the bed.
18. In a printing machine, the combination of a bed adapted to carry a printing form, a pivoted platen arm, a slideable carriage on the arm, a roller platen on the carriage, a spring attached to the carriage and tending to move it along the arm, link mechanism connected with the carriage tending to move it along the arm in opposition to the spring when the arm is raised, a latch carried by the arm and operating automatically to retain the carriage in the position in which the link mechanism has moved it, a manually depressible knob mounted on the platen arm, and means whereby the depression of such knob when the arm has been lowered may operate the latch to release the carriage, whereby the spring may cause the platen to roll over the form.
19. In a printing machine, the combination of a bed adapted to carry a printing form, a raiseable platen arm, a carriage slidably guided on the arm, a roller platen mounted in the carriage, a spring secured to the carriage and tending to move the carriage along the arm, mechanism connected to the carriage and operating when the arm is raised to move the carriage along the arm in opposition to the spring, means to hold the carriage in such constrained position, a latch to hold the arm temporarily elevated while allowing the arm to be readily lowered without releasing the carriage holding means.
20. In a printing machine, the combination of a bed adapted to carry a printing form, a platen arm pivotally mounted thereon and having a head adjacent the free end, a carriage slidably guided on the head, a roller platen mounted in the carriage, a tension spring secured to the carriage and anchored adjacent the pivot of the arm tending to move the carriage rearwardly along the arm, linkage mechanism connected to the carriage and operating when the arm is raised to move the carriage forwardly along the arm, a latch on the arm to hold the carriage in such constrained position, a second latch to hold the arm temporarily elevated while allowing the arm to be readily lowered without releasing the carriage latch, a depressible knob carried by the head, and mechanism operated by said knob to release the carriage latch, whereby the operator may by one action hold the platen arm down and release the platen to roll over the form.
21. In a machine for printing customer's tokens, the combination with a platen carrying arm, of a bed, a slide mounted thereon, means on the slide for removably carrying the token, different tokens having differently positioned notches in their edges, a movable pin adapted to bear against the edge of the token as inserted and enter the notch if properly positioned relative to the pin, a latch for the slide, a spring tending to move the slide into position to carry the token beyond the region of the platen, and means whereby the lowering of the arm may release the slide latch or leave it active according to the position of the control pin.
22. In a machine for printing customer's tokens, the combination of a bed, a slide mounted thereon and adapted to carry a token, spring means tending to move the slide and carry the token to an idle position, a latch for holding the slide in its active position, a platen arm carried by the bed and having a platen adapted to coact with the token on the positioned slide, a movable abutment carried by the bed, control mechanism on the bed having a pin adapted to enter a properly positioned notch in the edge of the token or engage the edge of the token if there is no notch in this location to vary the position of the abutment accordingly, means on the arm adapted to engage or miss the abutment upon lowering of the arm consequent upon the action of the control mechanism, and means whereby the engagement of the abutment causes a movement of the retaining latch for the slide, whereby the slide is released and its spring causes the movement of the token to idle position.
23. In a machine for printing customer's tokens, the combination of a bed, a slide thereon, means on the slide for removably carrying the token, an inking ribbon extending across the slide, a spring tending to move the slide into position to carry a token on the slide beyond the region of the ribbon, a platen adapted to coact with the token on the slide positioned beneath the ribbon to effect printing from the token, different tokens having differently positioned control characteristics thereon, and mechanism on the machine including means coacting with the control characteristic of the token to cause movement of the slide when an improperly characterized token is on the slide, whereby such token is carried out from under the inking ribbon.
24. In a machine for printing customer's tokens, the combination of a bed, a slide thereon, means on the slide for removably carrying the token,

token, an inking ribbon extending across the slide and overlying a token thereon or leaving the token exposed according to the position of the slide, a spring tending to move the slide into position to carry the token beyond the region of the ribbon, a latch for restraining the slide against such spring action, a movable platen arm carrying a platen adapted to coact with the token on the slide positioned beneath the ribbon to effect printing from the token, different tokens having differently positioned control characteristics thereon, and mechanism on the machine coacting with the control characteristic of the token and adapted to cause the platen arm when lowered to release the slide latch before the platen can coact with the token, whereby the token is carried out from under the inking ribbon.

25. A printing machine having a bed carrying an open ended shallow groove into which a customer's token may be slid by longitudinal movement, and a platen adapted to coact with the token when so held, combined with a customer's token composed of an embossed printing plate, a cover hinged to the end of the plate on an axis extending along such end, said cover serving to protect the plate when not in the machine

and acting as a handle for the insertion of the plate into the slideway of the machine or its withdrawal therefrom, and a member carried by the machine to support said cover when a token is placed in said groove.

26. In a printing machine, the combination of a bed, a slide carried thereby said slide having a shallow channel with overhanging ledges at its edges, the intermediate region of the slide being adapted to support a customer's token while the ledges overhang the edges of the token, a token adapted to be mounted on the slide and comprising a printing plate slideable beneath the ledges and a cover plate hinged to the end of the printing plate and adapted to engage and be supported by the slide near the hinge axis when the plate is inserted, whereby the cover acts as a handle for the insertion or removal of the plate, platen mechanism operating to print from the inserted token, and mechanism to release the slide when an improper token is mounted thereon, there being mechanism to move the released slide outwardly to carry such token to a non-printing position.
